J. H. TEMPLIN.
DISCHARGING DEVICE FOR VACUUM CLEANERS.
APPLICATION FILED NOV. 1, 1912.

1,080,789.

Patented Dec. 9, 1913.

UNITED STATES PATENT OFFICE.

JOSEPH H. TEMPLIN, OF PHILADELPHIA, PENNSYLVANIA.

DISCHARGING DEVICE FOR VACUUM-CLEANERS.

1,080,789.

Specification of Letters Patent.

Patented Dec. 9, 1913.

Application filed November 1, 1912. Serial No. 729,137.

To all whom it may concern:

Be it known that I, JOSEPH H. TEMPLIN, a citizen of Philadelphia, residing at Philadelphia, in the county of Philadelphia and 5 State of Pennsylvania, have invented certain new and useful Improvements in Discharging Devices for Vacuum-Cleaners, of which the following is a specification.

My invention relates to discharging devices for vacuum cleaners, more particularly 10 to that class of cleaners wherein the cleaner is passed bodily back and forth over the floor by means of a handle in the hand of the operator, and in which class, the dust 15 laden air passes through the cleaner into a receptacle, the lower end of which is connected to the discharging device and the upper end of the receptacle is connected to or near the upper end of the handle. The 20 upper end of this class of receptacles, as previously constructed rises and lowers with the handle, with the result, that in a vertical position, the receptacle closes the mouth of the discharge.

25 The object of my invention is to attain a free and unobstructed discharge of the dust laden air into the receptacle, and a further object is to attain a device whereby the receptacle can be easily and quickly connected 30 or disconnected as desired.

In the accompanying drawings which illustrate my device, similar numerals indicate like parts, and in which:

Figure 1 is a side elevation. Fig. 2 is a 35 plan of my device. Fig. 3 shows a retaining spring-catch. Fig. 4 is a section showing the retaining spring-catch in plan. Figs. 5 and 6 show modified forms of spring-catches.

40 In the drawings 1 is the main casing of the vacuum cleaner, 2 the motor case for driving the suction means and 3 is the base, provided with inlets at 4 and 5 in which the dust laden air is drawn.

45 6 is the discharge to which the lower end 7 of the dust receptacle is attached, 8 is the lower end of the handle attached to the cleaner at 9. The upper end of the dust receptacle is not shown, but may be one of any

of the well known constructions adapted to 50 cleaners of that class which are attached at or near the upper end of the handle.

In lieu of the stationary discharge mouth-piece, I attach an elbow 10 by means of the joint 11 around which the elbow is free to 55 vibrate, pivoted on pin 12 and retained in place by spring 13. Spring 13, as clearly shown in Fig. 4 is provided with a loop 14 whereby the spring can be grasped and drawn away to release the elbow. The opposite end of the spring is formed into a loop 16, a short end 17 of the spring extending radially so that when the loop of the spring is dropped into a pocket provided with a radial slot 18, the short end of said spring 65 serves as a resistance of the spring, and, due to the loop 16, an extra lateral movement can be attained on end 14 without fatiguing the resilience of the spring. Screw 19 retains the spring in place. While 70 I prefer the spring-catch as shown in Fig. 3, various other forms of catches as shown in Figs. 5 and 6 would perform the same functions.

With the foregoing description it can 75 readily be seen that during the operation of the device that, as the handle to which the upper end of the receptacle is attached, is raised or lowered, the tension of said receptacle on the freely revoluble or swivel 80 elbow causes the mouth of the same to follow the lines of tension resulting in a free and unobstructed discharge opening into said receptacle and further that the elbow can readily be removed from its seat for 85 cleaning or emptying the receptacle by simply releasing the spring-catch.

Having thus described my invention, what I claim and for which I desire Letters Patent is:

1. In a suction cleaner, a dust discharging outlet, a dust receptacle provided with an elbow inlet, said elbow revolubly seated on said outlet, and resilient means for retaining said elbow on said seat. 90

2. In a suction cleaner, a discharging outlet, a receptacle provided with a swivel inlet, and resilient means attached to said 95

discharging member, said means adapted to retain said swivel member seated on said discharging member.

3. In a suction cleaner, a discharging device, which comprises an air current generator provided with an outlet member, a dust receptacle provided with a swivel elbow member, and resilient means attached to said generator, said means adapted to re-

tain said swivel elbow member on said discharging outlet member. 10

In testimony whereof I affix my signature in presence of two witnesses.

JOSEPH H. TEMPLIN.
